UNITED STATES PATENT OFFICE

RUDOLF VON FROMMER, OF BUDAPEST, HUNGARY

SLIDING COVER FOR AUTOMATIC FIREARMS

Application filed October 27, 1930, Serial No. 491,571, and in Hungary October 29, 1929.

My invention relates to a sliding cover for automatic fire arms which covers the opening for ejecting the cartridge cases and the slit for the operating-handle of the breech-bolt with the object to protect the fire arm against penetration of dust and other impurities. Covers of this kind are already known, but are very complicated and dear. The cover according to the invention is rendered simple by connecting it with the pivot of the operating handle, making it in such a manner following the movements of the breech bolt.

In the accompanying drawing one preferred form of the invention is shown by way of example.

Fig. 1 is a side elevation of one part of a gun provided with the sliding cover in its closed position.

Fig. 2 is a top plane view of the same.
20 Fig. 3 is a cross sectional view taken on line III—III of Fig. 1.

Fig. 4 is a cross sectional view taken on line IV—IV of Fig. 1.

Fig. 5 is a side elevation of the sliding cover.
25 Fig. 6 is a top plane view of the sliding cover and

Fig. 7 is a cross section of the latter.

The sliding cover is composed of a jacket 30 1 shaped from a thin metal sheet according to the cross section of the breech casing 2, and is adapted to be shifted in the longitudinal direction. In its foremost position the jacket 1 covers the ejecting opening of the gun 35 whereas it uncovers the same in its rearmost position. The cover 1 is provided with an edge 3 guided in a recess 4 of the casing 2. On the right side of the casing there is arranged the operating handle 6 which can be pushed in a well known manner backwards and forwards whereby it is swung also in a known manner around its pivot 7, in order to facilitate the manual operation of the gun. To the end of allowing the shifting of the 40 operating handle a slot 9 is applied in the casing (see Fig. 3). In Figs. 1 and 2 the slot 9 is not visible, as it is covered by the jacket 1.

The right side of the jacket 1 is provided with an extension 10 which encircles the part 50 5 of the casing 2, this part 5 projecting along

the slot 9. This slot is completely covered by the extension 10. The jacket 1 is connected with the pivot 7 of the operating handle 6 so as to follow the breech bolt when the latter is being shifted, without hindering the swinging movement of the handle. This connection is effected for instance by means of a jaw 11 of the sliding cover, this jaw having bores 12 adapted to serve as bearings for the pivot 7.

When the handle is in its foremost position and the breech is closed, the ejecting opening as well as the slot 9 are completely covered.

In order to prevent hurting of the hand of the shooter when closing or opening the breech bolt respectively when the cover slides forwards or backwards in case of automatic operation of the fire arm, a projection 8 may be provided on the gun-stock such projection keeping the fingers of the shooter away from the cover. This projection is arranged under the path of the cover, so that a touching of the cover with the fingers can be avoided. Instead of the projection 8 integral with the gun-stock, a separate part of the same form 75 made of wood or iron can be secured on the gun-stock.

I claim:

1. In an automatic fire arm of the type having a breech bolt, a pivoted operating handle 80 on the breech bolt, a breech casing provided with a cartridge shell ejecting opening and with a slit enabling the operating handle to slide to and fro, a sliding cover covering the ejecting cartridge opening of the casing and 85 the slit for the operating handle, and means for connecting said sliding cover with the pivot of said operating handle so that it takes part in the movement of the breech bolt.

2. In an automatic fire arm, a pivotally mounted operating handle, a sliding cover covering the ejecting opening of the cartridge cases and the slit for the operating handle, means for connecting said sliding cover with the pivot of said operating handle and a projection of the gunstock arranged under the path of the cover and adapted to prevent touching of the cover by the fingers.

3. In an automatic fire arm, a pivotally mounted operating handle, a sliding cover 100

covering the ejecting opening of the cartridge cases and the slit for the operating handle, means for connecting said sliding cover with the pivot of said operating handle and a 5 separate part on the gunstock arranged under the path of the cover and adapted to prevent touching of the cover by the fingers.

In testimony whereof I affix my signature.
RUDOLF von FROMMER.
